UNITED STATES PATENT OFFICE.

RUDOLF V. HITSCHMANN, OF CLAFLIN, KANSAS.

ENVELOP-FASTENER.

1,079,598.

Specification of Letters Patent.

Patented Nov. 25, 1913.

Application filed April 9, 1913. Serial No. 759,976.

To all whom it may concern:

Be it known that I, RUDOLF V. HITSCHMANN, a citizen of the United States, residing at Clafflin, in the county of Barton, State 5 of Kansas, have invented certain new and useful Improvements in Envelop-Fasteners; and I do hereby declare the following to be a full, clear, and exact description of the invention, such as will enable others skilled in 10 the art to which it appertains to make and use the same.

This invention relates to envelop fasteners.

The object of the invention resides in the provision of an envelop fastener which may 15 be associated with various types of envelopes and when so associated will efficiently secure the closing flap of the envelop against movement of closing position.

A further object of the invention resides 20 in the provision of an envelop fastener which may be operated to secure the closure flap in closed position with ease and facility.

With the above and other objects in view the invention consists in the details of construction and in the arrangement and combination of parts to be hereinafter more 25 fully described and particularly pointed out in the appended claim.

In describing the invention in detail reference will be had to the accompanying drawings wherein like characters of reference denote corresponding parts in the several views, and in which—

Figure 1 is a rear elevation of an envelop provided with the improved fastener; Fig. 2, a section on the line 2—2 of Fig. 1; Fig. 3, a section on the line 3—3 of Fig. 1, and Fig. 4, a detail perspective view of one of the keeper members.

Referring to the drawings A indicates an envelop which includes a rear member 10 and a closing flap 11. Mounted in the free end of the flap 11 is a spring locking rod 12, said rod being disposed transversely of the 45 closing flap and having its ends projecting

beyond respective side edges of the flap. Held against the rear member 10 by means of straps 13 are oppositely disposed corresponding keeper members A and B. Each of these keeper members A and B is formed 50 of a plate 14 having a central raised portion 15, said raised portion being provided with a flange 16 disposed at right angles thereto. This flange 16 is provided with a plurality of perforations 17 for a purpose that will 55 presently appear.

In order to secure the closing flap in closed position the rod 12 is bowed so that said rod can be moved between the flanges 16 of the keeper members A and B. With the 60 rod 12 in this bowed state the ends thereof are engaged in corresponding openings 17 of the flanges 16 and then released to the influence of its resiliency. When so released the rod 12 will straighten and the ends of 65 same will pass through and project a considerable distance beyond the inner faces of the flanges 16. In this manner the closing flap 11 is efficiently secured against movement from closed position. 70

What I claim is:—

The combination with an envelop including a back member and a closing flap, of oppositely disposed corresponding keeper members secured against said back member, 75 each of said keeper members including a perforated portion disposed at right angles to the back member, and a locking rod carried by the free end of the closing flap, the terminals of said rod being adapted to be 80 detachably inserted in corresponding perforations of the keeper members respectively.

In testimony whereof, I affix my signature, in the presence of two witnesses.

RUDOLF V. HITSCHMANN.
